UNITED STATES PATENT OFFICE

96,453

DESIGN FOR A METALLIC ARTILLERY
WHEEL

Carolus L. Eksergian and Donald Alexander,
Detroit, Mich., assignors to Budd Wheel Com-
pany, Philadelphia, Pa., a corporation of
Pennsylvania

Application November 7, 1933, Serial No. 49,670

Term of patent 14 years

To all whom it may concern:

Be it known that we, Carolus L. Eksergian and Donald Alexander, citizens of the United States, residing at Detroit, in the county of Wayne and State of Michigan, have invented a new, original, and ornamental Design for a Metallic Artillery Wheel, of which the following is a specification, reference being had to the accompanying drawing, which forms a part hereof.

Figure 1 is a perspective view of our new wheel design.

Figure 2 is an enlarged fragmentary front elevation.

Figure 3 is an axial profile view, and

Figure 4 is a cross section through one of the spokes.

The wheel body portion of the design is its dominant feature, the hub cap and rim being relatively immaterial parts of the design.

We claim:

The ornamental design for a metallic artillery wheel as shown and described.

Signed at Detroit, county of Wayne, State of Michigan, this 3rd day of November, 1933.

CAROLUS L. EKSERGIAN.
DONALD ALEXANDER.
